UNITED STATES PATENT OFFICE.

HENRY R. GOGAY, OF COLUMBUS, OHIO, ASSIGNOR TO SOLAR METAL PRODUCTS COMPANY, INC.

HOLLOW METAL DOOR-FRAME.

1,323,755.

Specification of Letters Patent.

Patented Dec. 2, 1919.

Application filed October 24, 1917. Serial No. 198,266.

To all whom it may concern:

Be it known that I, HENRY R. GOGAY, a subject of the Crown of Great Britain, and resident of Columbus, in the county of 5 Franklin and State of Ohio, have invented a new and useful Improvement in Hollow Metal Door-Frames, of which the following is a specification.

In the manufacture of hollow metal door frames it has heretofore been impracticable 10 to complete the door frame until the strike plate to be used in connection therewith was known, thus preventing the stocking up of a large supply of door frames and also requiring 15 a special set of dies and tools for each particular size and style of strike plate.

The object of my invention is to produce a type of hollow metal door frame which may be completed in large quantities irrespective 20 of the size and style of strike plate to be used, thus materially reducing the cost of manufacture and also permitting the rapid filling of orders from stock. These results are accomplished by blanking out the door 25 jamb to fit a standard size sub-holder, the sub-holder in turn being blanked out to fit the particular strike plate to be used.

A practical embodiment of my invention is represented in the accompanying drawings 30 in which:

Figure 1 represents in face view, a portion of a door frame with my invention applied thereto.

Fig. 2 is a section taken in the plane of 35 the line II—II of Fig. 1.

Fig. 3 is a section taken in the plane of the line III—III of Fig. 2, and

Fig. 4 is a section taken in the plane of the line IV—IV of Fig. 1.

The door jamb 1 is blanked out to fit a sub-holder 2 of sufficient size to fit any required strike plate, and the sub-holder itself is in turn blanked out to fit the particular strike plate 3 intended for use with its particular door frame. The sub-holder 2 is preferably of channel form and it is secured to the door jamb by providing upper and lower clips 4 permanently secured to the door jamb, as for instance, by welding at suitable points as indicated by the dotted circles 4*, which clips have portions overlapping the top and bottom of the sub-holder. Screws 5 are provided for securing the top and bottom of the sub-holder to the 55 said clips 4.

The strike plate 3 is secured to the sub-holder by providing the sub-holder with clips 6 permanently secured to the sub-holder, as for instance, by welding at suitable points as indicated by the dotted circles 6*, which clips have portions overlapping the top and bottom of the strike plate. Screws 7 serve to secure the top and bottom of the strike plate to the said clips.

In applying the strike plates to the door 65 frame, the sub-holder is blanked out to fit the particular strike plate to be used, the clips 6 are secured to the sub-holder and after the strike plate has been fitted to the blanked out portion of the sub-holder, the screws 7 70 serve to fasten the strike plate to the sub-holder. The sub-holder is then fitted into the blanked out portion of the door jamb and the screws 5 are used for securing the sub-holder in position.

While I have shown the invention as applied to the attachment of any size and style of strike plate to a door frame, it is obvious that the same may be used in connection with hollow metal construction anywhere 80 where a strike plate can be applied. Hence, I do not wish to limit myself to the particular application herein shown and described, but—

What I claim is:

1. In a hollow metal door frame arranged to receive strike plates of various sizes and styles, a sub-holder blanked out to fit a particular strike plate, the jamb being blanked out to fit the sub-holder, and means 90 for securing the strike plate to the sub-holder.

2. In a hollow metal door frame arranged to receive strike plates of various sizes and styles, a channel-shaped sub-holder blanked 95 out to fit a particular strike plate, the jamb being blanked out to fit the sub-holder, and means for securing the strike plate to the sub-holder.

3. In a hollow metal door frame arranged 100 to receive strike plates of various sizes and styles, a sub-holder blanked out to fit a particular strike plate, the jamb being blanked out to fit the sub-holder, and means for securing the sub-holder to the jamb.

4. In a hollow metal door frame arranged 105 to receive strike plates of various sizes and styles, a channel-shaped sub-holder blanked out to fit a particular strike plate, the jamb being blanked out to fit the sub-holder, and 110

means for securing the sub-holder to the jamb.

5. In a hollow metal door frame arranged to receive strike plates of various sizes and 5 styles, a sub-holder blanked out to fit a particular strike plate, the jamb being blanked out to fit the sub-holder, and means for securing the strike plate to the sub-holder and the sub-holder to the jamb.

10. 6. In a hollow metal door frame arranged to receive strike plates of various sizes and styles, a channel-shaped sub-holder blanked out to fit a particular strike plate, the jamb being blanked out to fit the sub-holder, and 15 means for securing the strike plate to the sub-holder and the sub-holder to the jamb.

7. In a hollow metal door frame arranged to receive strike plates of various sizes and styles, a sub-holder blanked out to fit a particular strike plate, the jamb being blanked out to fit the sub-holder, clips carried by the sub-holder overlapping the strike plate and screws for securing the strike plate to the clips.

25. 8. In a hollow metal door frame arranged to receive strike plates of various sizes and styles, a channel-shaped sub-holder blanked out to fit a particular strike plate, the jamb being blanked out to fit the sub-holder, clips 30 carried by the sub-holder overlapping the strike plate and screws for securing the strike plate to the clips.

9. In a hollow metal door frame arranged to receive strike plates of various sizes and 35 styles, a sub-holder blanked out to fit a particular strike plate, the jamb being blanked

out to fit the sub-holder, clips carried by the jamb overlapping the sub-holder and screws for securing the sub-holder to the clips.

10. In a hollow metal door frame arranged to receive strike plates of various sizes and styles, a channel-shaped sub-holder blanked out to fit a particular strike plate, the jamb being blanked out to fit the sub-holder, clips carried by the jamb overlapping the sub-holder and screws for securing the sub-holder to the clips. 40 45

11. In a hollow metal door frame arranged to receive strike plates of various sizes and styles, a sub-holder blanked out to fit a particular strike plate, the jamb being blanked out to fit the sub-holder, clips carried by the sub-holder and jamb overlapping the strike plate and sub-holder respectively, and screws for securing the strike 50 55 plate to its clips and the sub-holder to its clips.

12. In a hollow metal door frame arranged to receive strike plates of various sizes and styles, a channel-shaped sub-holder blanked out to fit a particular strike plate, the jamb being blanked out to fit the sub-holder, clips carried by the sub-holder and jamb overlapping the strike plate and sub-holder respectively, and screws for securing 60 65 the strike plate to its clips and the sub-holder to its clips.

In testimony that I claim the foregoing as my invention I have signed my name this 10th day of August, 1917.

HENRY R. GOGAY
